CLAIM

The ornamental design for a display screen with animated graphical user interface, as shown and described.

DESCRIPTION

FIG. 1.1 is a front view of a display screen with animated graphical user interface;

FIG. 1.2 is a second image thereof; and,

FIG. 1.3 is a third image thereof.

The outer broken lines in the figures show a display screen or portion thereof, or an electronic device having a display screen, and form no part of the claimed design. The appearance of the transitional image sequentially transitions between the images shown in FIGS. 1.1-1.3. The process or period in with one image transitions to another image forms no part of the claimed design.
